SPATULA

William Marcus, Cleveland, Ohio, assignor to Merrymaid
Plastics Corp., Cleveland, Ohio, a corporation of Ohio

Filed Aug. 1, 1960, Ser. No. 61,575

Term of patent 14 years

(Cl. D44—29)

This application is a continuation-in-part of my application Serial No. D. 58,213, filed November 5, 1959, now abandoned.

I claim:

The ornamental design for a spatula, as shown and described.
